(57) **CLAIM**

The ornamental design for a support for accessories, as shown and described.

DESCRIPTION

FIG. 1 is a front top right perspective view of our new design;

FIG. 2 is a rear view thereof;

FIG. 3 is a top view thereof;

FIG. 4 is a front view thereof;

FIG. 5 is a bottom view thereof;

FIG. 6 is a left side view thereof, the right side view being a mirror image thereof;

FIG. 7 is a top rear perspective view of our new design incorporated into a beverage caddie;

FIG. 8 is a front top left perspective view of our new design incorporated into a first bracket; and,

FIG. 9 is a front top right perspective view of our new design incorporated into a second bracket.

The jagged dash-dot lines bridged by a bracket in each figure represents a symbolic break in length of the support. The appearance of any portion of the article between the break lines forms no part of the claimed design such that the precise length of the support forms no part of the claim. The dash-dot lines elsewhere in the figures represent optional environmental features that form no part of the claim. The dash-dot lines in the figures illustrate unclaimed boundaries of the design along claimed surfaces.

1 Claim, 6 Drawing Sheets
